UNITED STATES PATENT OFFICE

WILLIAM A. KNAUS, OF ONEIDA, NEW YORK, ASSIGNOR TO NATIONAL CASKET COMPANY, A CORPORATION OF NEW YORK

BURIAL CASKET

Application filed April 20, 1927. Serial No. 185,317.

Caskets are made in various designs to satisfy the tastes of different people. The main object of my present invention is to produce a construction which is at once solid and substantial and yet provided with means for producing the attractive ornamental appearances of other constructions. Various ornamental display effects have been produced by dividing the sides and top of the casket 10 so that the sides may be opened sectionally. Such constructions are, however, expensive to make and are likely to become warped out of shape unless very carefully constructed.

In a sense, my invention constitutes an improvement upon the construction of the Mac- 15 Donald Patent, #1,500,141 dated July 8, 1924. I have endeavored to simplify and perfect this construction so as to reduce the cost of installation, facilitate the adjustment 20 of the parts and make the finished construction more compact.

The casket body or shell may have any design and be made of any material. The body or shell may be of the regular solid or uncut 25 type so as to preserve all the possible strength of the material and avoid joints or cracks. The invention contemplates an attachment as applied to caskets regardless of the type of cover or top, hinged or detachable. I also 30 wish it understood that the invention is applicable to constructions having the cover either in one piece or in two pieces and that it may be applied to the full length or half length of the casket, as desired. Expressed 35 in its simplest terms the invention properly contemplates the provision of a skeleton like frame hinged along one or more edges of the casket and adapted to be folded up snugly within the casket or extended out over the 40 sides or ends at various angles. This frame is covered with suitable padding or ornamental material made according to any desired design.

Fig. 1 is a front view of one form of casket with a two piece cover, one part being shown raised and the ornamental lining displayed or spread out so as to give the appearance of a regular half couch.

Fig. 2 is a transverse sectional view on

a somewhat larger scale showing the cover raised and the lining spread out.

Fig. 3 is a fragmentary transverse sectional view showing the lining and frame folded up inside the shell and the cover closed.

Fig. 4 is a detail view on a somewhat larger scale showing end and side frames in variously adjusted positions.

Fig. 5 is a perspective view of one of the folding frames.

Fig. 6 is a perspective view showing a modified detail of construction.

The body or shell 10 may be of any suitable design, construction or material, but preferably with the sides, ends and bottom 65 solidly and permanently constructed and secured together, to provide as much strength as possible and without cracks, joints or hinges. The cover or top may be in one or more pieces. In the form herein shown there 70 are two parts 11 and 12, which are detachable or hinged or both, as desired, according to any approved casket construction. These cover sections are also solid and substantial 75 and without joints, or cracks.

It should, of course, be understood, however, that the upper section 11 might have a detachable panel 13 of any suitable form. The construction might also be provided with an internal glass or screen (not shown) in 80 any well known manner.

The folding frame which in a sense constitutes an attachment for a standard type casket, is made up of one or more articulated 85 hinges formed of metal. The various sections 14, 15 and 16 of one of these hinges are hinged to each other at 17 and 18 by any suitable form of frictional hinge design so that the hinges may be set up tight enough to hold the parts in any desired position and yet permit the parts to be folded into various positions as shown in Fig. 4. The section 14 is adapted to be secured to the inner wall 19 of the shell in such a position that the joint 90 17 comes substantially on a level with the upper edge of the shell. When the parts are spread out fully the section 15 will therefore rest upon the upper edge of the shell. When the parts are folded up inside the shell they 95 100

take up one of the positions shown in Fig. 4 fitting snugly against the inside of the shell.

The sections 15 and 16 are connected together by longitudinal wires or rods such as 20 and 21 to support the ornamental lining 22 and any padding 23 which it may be desired to use. This lining may be of any suitable material such as silk, quilted or ornamental, in any suitable manner and it may be secured in place within the casket shell and to the folding frame in any desired manner. The end of the shell may be provided with a similar folding frame and lining section 24 adjustable independently of the front frame both inside and outside of the shell. The cover may also be provided with an ornamental lining 25 of any suitable design or material.

The lining may be stitched or otherwise secured to the folding frame. In Fig. 6 I have shown the outer sections 16 as provided with an extension 26 which has a snap member 27 adapted to receive a companion snap (not shown) attached to the lining.

According to my invention the attachments may be so arranged and adjusted as to produce the effect of a drop side casket without the disadvantage of the weakening by cutting or hinging the parts of the shell. By having the ends and sides adjustable independently of each other it is possible with the same construction to display the casket with a full or half couch effect or with a third drop side effect. By folding the support entirely within the shell, the casket will have the appearance of a regular casket without any externally visible adjustments or extensions. Thus a dealer may display the casket in various different ways to illustrate to a customer different designs and effects. He thus can convert the casket in its various forms without the necessity of carrying a large number of styles which may become obsolete as styles change.

I claim:

The combination with a burial casket, of a supporting frame adapted to be compactly foldable adjacent an inner face of a casket wall and extensible outside said casket, said frame comprising spaced multi section hinge members, the inner sections of each member being secured to the inner face of a casket wall with the joint between said inner section and its adjacent section located at substantially the top of the supporting wall to allow said adjacent section to be supported contiguous and substantially horizontal across the top of the casket wall the outer sections of each hinge member being movable to extend laterally outside and away from the said supporting wall, a thin rod connecting the hinge members adjacent their outer joints and the outer end portions of the outermost hinge sections to constitute a support for a flexible cover for said frame; the materials of the

frame and cover when folded inside the casket being no thicker between said hinge members than the thickness of said rods and the layers of the flexible cover, and the outermost section of each hinge member being constructed to be foldable under the adjacent section of the same member when said adjacent section is laterally extended.

WILLIAM A. KNAUS.
